ATTORNEY.

UNITED STATES PATENT OFFICE.

JOHN W. THOMAS, OF KANSAS CITY, KANSAS, ASSIGNOR OF ONE-HALF TO JOHN E. HAMILL, OF KANSAS CITY, MISSOURI.

RAILWAY-TIE PLATE.

1,143,559.

Specification of Letters Patent. Patented June 15, 1915.

Application filed December 17, 1913. Serial No. 807,230.

To all whom it may concern:

Be it known that I, JOHN W. THOMAS, a citizen of the United States, residing at Kansas City, in the county of Wyandotte 5 and State of Kansas, have invented certain new and useful Improvements in Railway-Tie Plates, of which the following is a specification.

My invention relates to improvements in 10 railway tie-plates, and one object is to provide a simple and inexpensive device of this character which will securely hold a rail laid thereon from creeping, or rattling when a train travels thereover.

15 Among other features, the invention embodies means that automatically take up slack between the tie-plate and the rail, so that the latter is always held firmly upon the former.

20 In order that the invention may be fully understood, reference will now be made to the accompanying drawing, in which: Figure 1 is a cross sectional view of a rail and my tie-plate on line I—I of Fig. 2, in position upon a cross-tie. Fig. 2 is a plan view 25 of the tie-plate and the rail, the latter being in section on line II—II of Fig. 1. Fig. 3 is a detail perspective view of a locking member for securing one side of the rail and 30 tie-plate together.

Referring now in detail to said drawing, 1 designates the tie-plate which is wider than the base of the rail A; as shown on Figs. 1 and 2, to provide a broad bearing 35 surface upon the underlying cross-tie B.

The underside of the tie-plate is provided with a pair of longitudinal V-shaped teeth 2, which become embedded in the top of the cross-tie and thus assist spikes C in holding 40 said tie-plate in proper position. The upper portion of the tie-plate, near one side thereof, has a longitudinal flange 3 with a beveled upper surface 4. Flange 3 is adapted to abut the adjacent side of the rail base, 45 and thus prevent lateral movement of the rail A in the direction of said flange 3. The inner vertical side of flange 3 has a series of teeth 5, which become embedded in the abutting edge of the rail base and 50 thus prevent the same from creeping longitudinally upon the tie-plate.

6 designates a lip on the tie-plate adapted to overlap the opposite side of the rail base from that abutting the flange 3. Lip 6 is provided with a centrally-disposed aperture 55 7, for the reception of a tapered locking member 8 provided at its reduced end with an upwardly extending head 9 to prevent it from being driven through the aperture 7. Head 9 is protected from injury by a 60 pair of oppositely-disposed guard members 10 integral with the tie-plate.

In practice one side of the rail base is placed beneath the lip 6, while the opposite side of said base is placed upon the beveled 65 upper surface 4 of flange 3, after which sufficient weight is applied to the top of the rail to cause it to slide down from said beveled surface 4 to the position shown in Fig. 1. Spikes C are then driven through 70 openings 11 in the tie-plate to secure the same to the underlying cross-tie and also to hold the side of the rail base abutting the flange 3.

The opposite side of the rail base is then 75 wedged firmly upon the tie-plate 1 by driving the locking member 8 downward in the direction of its head 9. Owing to the tapered shape of the locking member 8 and the inclined position it occupies while in 80 use, it will automatically take up any slack between the tie-plate and the rail and thus prevent rattling of the latter upon the former.

Having thus described my invention, what 85 I claim and desire to secure by Letters Patent is:

In combination, a tie-plate, a lip on said tie-plate having an opening therein and adapted to overlap one side of a rail base, 90 oppositely disposed guard members adjacent the opening in the lip, and a tapered locking member extending through the opening in the lip and adapted to engage the rail base.

In testimony whereof I affix my signature, in the presence of two witnesses.

JOHN W. THOMAS.
